CLYDE C. MANCHESTER, OF TOLEDO, OHIO, ASSIGNOR TO THE AYLING & REICHERT COMPANY, OF TOLEDO, OHIO, A CORPORATION OF OHIO.

METHOD AND MACHINE FOR SEPARATING FLANGED NESTED STAMPINGS.

Application filed January 24, 1927. Serial No. 163,204.

This invention relates to a method and machine for separating flanged, nested stampings. Flanged stampings, particularly for float shells, are sometimes formed in pairs by running two ribbons of sheet metal through a stamping machine at the same time, one above the other, and forming the stampings by a single pair of dies, such procedure having certain advantages from a manufacturing standpoint. When so formed there is, of course, a very close union between the individuals of each pair of stampings, and the operation of separating them manually is rather difficult, and therefore slow and costly.

One object of this invention is the provision of a simple method and machine for performing this work of separating such nested stampings with a considerable decrease in the amount of labor involved.

Another object is the provision of mechanical means for holding and directing a pair of stampings so that their flanges may be presented to the point of an elongated wedge, and the wedge and stampings caused to move relatively so that the tapered walls of the wedge gradually spread the flanges apart and break the union between the stampings.

Another object is the provision of means for stripping one of the stampings of a pair from the machine in one position of the holder and the other stamping in a further advanced position, so that all the inner stampings are automatically collected and kept separate from the outer stampings.

A further object is the provision of a machine of the character stated in which the travel of the stampings is in the arc of a circle, so as to permit the use of a wedge of considerable length, in spite of the fact that the machine occupies but little floor space, and along a very gradually tapered wedge enabling the machine to exert steady and heavy pressure for a minimum of power.

Other objects will appear as I proceed with the description of one embodiment of the invention which, for the purposes of

the present application, I have illustrated in the accompanying drawings, in which:

Fig. I is a front elevational view of the complete machine.

Fig. II is a side elevation of the same.

Fig. III is a detail elevational view of the plate which carries the wedge, but with the wedge removed.

Fig. IV is a cross-sectional view of the plate, taken substantially on the line IV—IV, Fig. III.

Fig. V is a detail perspective of the stripping finger for the outer stamping.

Fig. VI is a detail perspective of the stripping finger for the inner stamping.

Fig. VII is a detail perspective of a flared guide which is employed to direct the nested stampings into close contact with the plate and thus into position to be properly engaged by the wedge.

Fig. VIII is a detail front elevation of the main section of the wedge bar.

Fig. IX is a developed view of the outer edge of the same.

Fig. X is a section taken substantially on the line X—X, Fig. VIII.

Fig. XI is a detail, partly in section, of one of the holders for the nested stampings.

Fig. XII is a detail perspective view of the forward or knife-blade section of the wedge bar.

Fig. XIII is a fragmental cross-section of the plate with the wedge bar assembled thereon, the section being taken substantially on the line XIII—XIII, Fig. I.

Fig. XIV is a fragmental detail plan view of the revolving arm with a pair of nested stampings thereon.

Fig. XV is a rear elevational view of the arm, its supports for nested stampings, and the ring gear by which it is moved, and

Fig. XVI is an elevational view showing a pair of stampings in the process of being separated.

Similar reference characters refer to like parts throughout the views.

In the drawings, the machine is disclosed as built upon one short front leg 10, and

two longer rear legs or standards 11, the bed 12 of the machine being supported upon the top of the leg 10, and being provided with suitable holes through which the standards 12 extend and by which the bed is supported through the intermediacy of collars 13 to which the bed 12 is bolted. On the top of standards 11 is supported a cross-beam 14 upon which may be mounted an electric motor 15 which may be employed to drive the belt 16 running over a pulley 17, fast upon a shaft 18, the rear bearing for which is mounted upon a cross brace 19 and the front bearing for which is located in a supporting block 20, which is bolted to one side of the front leg 10.

On its outer end the shaft 18 carries a pinion 21 which meshes with a ring gear 22 of considerable size. As shown in Fig. XV, this gear is bolted upon an arm 23 in the mid position of the latter. The gear 22 and arm 23 are together journaled upon a supporting spindle 24, mounted in blocks 25 and 26 bolted to the upper surface of the bed 12. On the ends of the arm 23 and on the front face thereof I mount holders 27, shown in detail in Fig. XI. Each of these holders is drilled at the center to take the outer diminished diameter portion of a stud 28, the holder 27 being retained upon the stud by means of a set-screw 29, as will be apparent from the drawing. The opposite end of the stud is of a still smaller diameter to extend through a hole in the arm 23, and is threaded to take a nut 30 by means of which the stud is held in position upon the arm.

The spindle 24, which is prevented from turning, as by means of pin 31 in block 26, carries at its forward end a plate 32 which is drilled at 33^A to receive the spindle. The plate is fixed, being locked to the spindle against both bodily and rotary movement by a locking pin 34 as indicated by dotted lines in Fig. I. On its front face at the periphery, plate 32 is rabbeted very slightly, as at 33, so as to provide sufficient room behind the main surface of the plate to accommodate the flange of one stamping. An arc-shaped bar, flat on its rear surface, is secured to the plate 32 at the periphery of the latter, thus forming with rabbet 33 a groove shown clearly in Fig. XIII. The bar mentioned is composed of a main section 35, shown in detail in Fig. VIII, and a smaller forward or knife-blade section 36. Both of these sections are rigidly secured to the plate 32 by suitable means such as bolts or machine screws extending through holes 37 and 38 respectively in the sections, the rear edge of the section 36 being butted against the forward edge of section 35 when the parts are assembled.

In front of the section 36 I mount a flared guiding strip 39, the holes 40 in this strip registering with the holes 38 in the bar sec-

tion 36 so that the two pieces may be mounted by means of one set of fastenings. The front faces of the bar sections 35 and 36 are also rabbeted, as at 41, for a distance inward from the periphery substantially 70 equal to the width of the rabbet 33, both rabbets being wide enough to easily accommodate the flanges on the stampings. The depth of the rabbet 41, however, is not constant, but decreases continuously from its 75 forward end to its rear end as shown in Fig. IX, thereby producing a long, gradual taper on the front side of the bar sections 35 and 36, which, taken with the flat surface at the rear of the sections forms an 80 arc-shaped wedge running down to a point or knife-edge in the section 36.

A notch 42, cut into the face of bar section 35, receives an arm 43 extending laterally from a stripping finger 44 lying upon the face of the rabbet 41 and sharpened at its forward edge 45 so as to ride under the flange of a stamping passing over it. The rear end of the stripping finger is outwardly flared at 46 to guide the stamping outward. 90 The stripping finger is secured to the bar section 35 by means of machine screws 47.

At the rear end of the bar section 35 is a second stripping finger 48 which has a depressed lip 49, sharpened at its forward edge, lying against the bottom of the rabbet 33 and adapted to run under the flange of a stamping and guide it outwardly. The rear end of the finger 48 is flared outwardly 100 at 50 for assisting in the dumping of the stamping.

The arm 23 on the forward side of each end thereof carries a pair of studs or pins 51 which are flat at their ends and constitute abutments for the flanges of the stampings. The ends of this arm also have ribbon metal catches 52 which are free to swing on pivots 53 at the rear side of the arm and act automatically by gravity as will presently appear.

Operation.—The flanged metal stampings, which I have indicated at 54 in Figs. XIV and XVI, are received by the operator of this machine in pairs nested together, as indicated in Fig. XIV. He grasps a pair and places it upon one of the holders 27 as the latter moves with the arm 23 in a clockwise direction, viewing the machine as in Fig. I, while the arm is moving up into horizontal position. The flanges of the stampings then rest at one side in the rabbet 33 on the plate 32 and at the other side upon the studs or pins 51. The holder 27 is so constructed as to closely fit within the stampings and thus prevent sidewise movement thereof. The operator holds the stampings thus in position until the flanges have been engaged by the flared strip 39 and directed by it into close engagement with the surface of the 130

rabbit 33 and until the knife edge of the wedge section 36 under the strip 39 has been presented to the joint between the flanges and has begun to pass between them and until the catch 52 has descended by gravity to take the position indicated by full lines in Fig. XIV. The stampings are then retained by the catch 52 on one side and by the wedge on the other side, and the operator 10 may release his hold and pick up another pair of stampings to be placed upon the other holder 27 when it comes into position for him to do so.

Following the first pair of stampings as it 15 moves around the plate 32, the flanges on the side where they are engaged over opposite surfaces of the wedge, are very gradually but continuously spread apart. When they come into a position at the right of the 20 machine slightly below the center of the plate 32 the catch 52 swings down by gravity away from the stampings. By this time the tight union between the stampings is broken, and as they come opposite the finger 44 the 25 outer loosened stamping is suddenly deflected outwardly at its side nearest the center of the plate 32 until it overbalances and drops from the machine into a suitable receptacle (not shown). The other stamping 30 however is still held on the holder 27 because of the fact that its flange still lies within the rabbit 33 between the plate 32 and the wedge. However, when it passes the 35 end of the wedge it is caught by the lip 49 on stripping finger 48 and deflected outwardly sufficiently to be dumped by gravity.

The machine can be run fast enough to 40 keep one operator busy feeding nested stampings, and the labor involved is obviously very light while the number of pairs of stampings which can be separated in a given length of time equals what several experienced workmen can accomplish by hand.

To those skilled in the art it will be 45 obvious that various changes in detail construction may be resorted to without departing from the spirit of the invention. In the broader aspects of the invention it is immaterial whether the wedge moves or whether the holder moves, so long as there is relative motion between these parts. Hence, I 50 do not desire to be bound by any limitations except such as are included in the appended claims.

55 I claim as my invention:

1. The method of separating flanged, nested stampings, which consists in moving a pair of nested stampings along a flat surface with a wedge spaced therefrom by approximately the thickness of one flange, causing said wedge to enter and advance between the flanges, stripping the outer stamping from the pair after the flanges of the pair have been wedged apart sufficiently to loosen 60 the union between the stampings, and remov-

ing the remaining stamping after it has passed the butt end of the wedge.

2. In a machine for separating flanged, nested stampings, a flat base, a wedge mounted upon said base but spaced therefrom sufficiently to permit the flange of one stamping to move freely therebetween, means for holding a pair of nested stampings so as to present the joint between flanges along one side of the stampings to the point of the wedge, means for producing relative motion between said stampings and wedge along one edge of the latter, and means for stripping the outer of said stampings from the machine after the union between stampings has been loosened by said wedge while the inner of said stampings is still held by its flange between said base and wedge. 70

3. In a machine for separating flanged, nested stampings, a flat base, a wedge mounted rigidly with respect to said base and spaced therefrom throughout its length sufficiently to permit one flange to move freely between said base and wedge, a holder for supporting a pair of nested stampings, means for producing relative motion between said holder and wedge so as to cause the stampings to engage the point of the wedge at the joint between the flanges along one side of the stampings and to continue engagement along one edge of the wedge, and means for stripping the outer of said stampings from the machine after the union between stampings has been loosened by said wedge while the inner of said stampings is still held by its flange between said base and wedge. 80

4. In a machine for separating flanged, nested stampings, an elongated wedge, a holder for stampings, means for causing the point of said wedge to pass between the flanges of two adjacent stampings and for causing its tapering walls to advance between said flanges to separate the latter and break the union between said stampings, 90 means for stripping the outer one of the stampings from the machine before the relative motion between the holder and wedge is completed and means for holding the flange of the other stamping against the opposite side of the wedge until the relative motion between the holder and wedge is completed. 100

5. In a machine for separating flanged, nested stampings, an arcuate wedge, a holder for stampings, said wedge and holder being capable of relative rotary motion about the center of the circle from which the arc of said wedge is struck, means for causing said relative motion, the holder and wedge being so positioned that the joint between the flanges of said stampings along one side of the latter will be presented during the course of said motion to the point of the wedge, whereby the tapered walls of the wedge will gradually spread the flanges 110 115 120 125 130

- apart and break the union between the stampings, means upon one wall of said wedge for stripping one stamping from the machine before the relative motion between holder and wedge is completed, and means for holding the flange of the other stamping against the opposite wall of the wedge until the said relative motion is completed.
6. In a machine for separating flanged, nested stampings, a wedge formed along an arc of a circle, an arm mounted to turn about the center of said circle, a holder for stampings mounted upon the free end of said arm at a radius such as to bring the flanges of the stampings on the side towards the wedge into circular alignment therewith, means for moving said arm to cause the point of the wedge to enter between the flanges and to cause the tapered walls of the wedge to gradually spread the flanges and break the union between the stampings, means upon one wall of the wedge for stripping one stamping from the machine before the holder has traversed the entire length of the wedge, and means for retaining the flange of the other stamping against the opposite wall of the wedge until the holder has passed the butt end of the wedge.
7. In a machine for separating flanged, nested stampings, a wedge formed along an arc of a circle, an arm mounted to turn about the center of said circle, a holder for stampings mounted upon the free end of said arm at a radius such as to bring the flanges of the stampings on the side towards the wedge into circular alignment therewith, means for moving said arm to cause the point of the wedge to enter between the flanges and to cause the tapered walls of the wedge to gradually spread the flanges and break the union between the stampings, a catch upon said arm for engagement over the flanges on the side of the stampings furthest removed from the wedge, means upon one wall of the wedge for stripping one stamping from the machine before the holder has traversed the entire length of the wedge, said catch being automatically disengaged just prior to said stripping operation, and means for retaining the flange of the other stamping against the opposite wall of the wedge until the holder has passed the butt end of the wedge.
8. In a machine for separating flanged, nested stampings, a circular plate, a wedge formed along a portion of the periphery of said plate and spaced therefrom by approximately the thickness of one stamping flange, an arm with a pivotal connection at the center of said plate, a holder for stampings mounted upon the free end of said arm at a radius such as to bring the flanges of the stampings on the side towards the wedge into circular alignment therewith, means for producing relative rotary motion be-
- tween said plate and arm to cause the point of the wedge to enter between the flanges and to cause the tapered walls to gradually spread the flanges and break the union between the stampings, means for stripping the outer stamping from the machine before the relative motion between the holder and wedge is completed, the flange of the other stamping being retained between the plate and wedge until the said relative motion is completed.
9. The method of separating flanged nested stampings which consists in moving a pair of nested stampings along a flat surface with a wedge spaced therefrom by approximately the thickness of one flange, causing said wedge to enter and advance between the flanges sufficiently to loosen the union between the stampings, removing one stamping, and removing the remaining stamping after it has passed the butt end of the wedge.
10. In a machine for separating flanged nested stampings, an elongated wedge with its tapering walls longitudinally extending, a holder for stampings, and means for causing the point of said wedge to pass between the flanges of two adjacent stampings and for causing its tapering walls to advance longitudinally between said flanges to separate the latter and break the union between said stampings.
11. In a machine for separating flanged nested stampings, an arcuate wedge, a holder for stampings, said wedge and holder being capable of relative rotary motion about the center of the circle from which the arc of said wedge is struck, and means for causing said relative motion, the holder and wedge being so positioned that the joint between the flanges of said stampings along one side of the latter will be presented during the course of said motion to the point of the wedge, whereby the tapered walls of the wedge will gradually spread the flanges apart to break the union between the stampings.
12. In a machine for separating flanged nested stampings, a wedge formed along an arc of a circle, an arm mounted to turn about the center of said circle, a holder for stampings mounted upon the free end of said arm at a radius such as to bring the flanges of the stampings on the side towards the wedge into circular alignment therewith, and means for moving said arm to cause the point of the wedge to enter between the flanges and to cause the tapered walls of the wedge to gradually spread the flanges and break the union between the stampings.
13. In a machine for separating flanged nested stampings, a circular plate, a wedge formed along a portion of the periphery of said plate and spaced therefrom by ap-

proximately the thickness of one stamping flange, an arm with a pivotal connection at the center of said plate, a holder for stampings mounted upon the free end of said arm at a radius such as to bring the flanges of the stampings on the side towards the wedge into circular alignment therewith, and means for producing relative rotary motion

between said plate and arm to cause the point of the wedge to enter between the flanges and to cause the tapered walls thereof to gradually spread the flanges and break the union between the stampings.

In testimony whereof I affix my signature.

CLYDE C. MANCHESTER.
